DESIGN FOR A CABINET FOR AIR CONDITIONING APPARATUS OR SIMILAR ARTICLE

Oscar C. Palmer, Phoenix, Ariz.

Application October 19, 1934, Serial No. 53,690

Term of patent 3½ years

To all whom it may concern:

Be it known that I, Oscar C. Palmer, a citizen of the United States, residing at Phoenix, in the county of Maricopa and State of Arizona, have invented a new, original, and ornamental Design for a Cabinet for Air Conditioning Apparatus or Similar Article, of which the following is a specification, reference being had to the accompanying drawing, forming a part thereof.

Referring to the drawing:

Figure 1 is a view in front elevation of the article, showing my new design,

Figure 2 is a top plan view, and

Figure 3 is a horizontal sectional view taken upon the lines 3—3 of Figure 1 with the direction of view as indicated.

I claim:

The ornamental design for a cabinet for air conditioning apparatus or similar article, as shown and described.

OSCAR C. PALMER.
